UNITED STATES PATENT OFFICE.

BENJAMIN WOLHAUPTER, OF NEW ROCHELLE, NEW YORK, ASSIGNOR TO THE RAIL JOINT COMPANY, OF NEW YORK, N. Y., A CORPORATION OF NEW YORK.

CROWNED-BASE RAIL-JOINT.

1,103,460.

Specification of Letters Patent. Patented July 14, 1914.

Application filed February 11, 1913. Serial No. 747,824.

To all whom it may concern:

Be it known that I, BENJAMIN WOLHAUPTER, a citizen of the United States, residing at New Rochelle, in the county of 5 Westchester and State of New York, have invented certain new and useful Improvements in Crowned-Base Rail-Joints, of which the following is a specification.

This invention relates to rail joints of 10 the type having a crowned-base for supporting the rail ends.

The crowned-base type of rail joint possesses a number of practical functional characteristics and advantages that are provided for and maintained in a very effective manner by the present invention. Among the more important objects of a joint of this character is to properly distribute the load from the rails through the 20 joint to the ties, and as the crowning rail seat and support provides means whereby the load is transmitted, only through the center of the joint to the ties, the very common "pumping" up and down of the ties 25 is eliminated to a maximum extent, and at the same time the loads are distributed in such a way as to avoid displacing of the ties or the loosening of the road-bed. Furthermore, a rail joint having the crowned- 30 base characteristic referred to confines the tight fit of the joint to the rail base at the ends of the rails only, with the consequence that the end bolts of the joint may be tightened to any degree without liability of kinking 35 the rails, and the wave motion in the rails under load is transmitted more evenly through the joint with less upward movement of the rail ends, than in a joint having a tight base support throughout its length.

Accordingly, an object of the present invention is to provide a construction wherein in the full effect of the crowned-base support is obtained in a rail joint and means provided whereby the alinement of the rails 45 and tie bolts may be maintained under all conditions of adjustment.

Furthermore, a special and important object of the invention is to provide a crowned-base rail joint whose construction 50 is of such a character as to make it possible to secure the crowned-base support by the manipulation and development of a base plate only, thus permitting the side bars of the joint to be of conventional form and re-

main unchanged, and requiring no pressing 55 or special rolling operations.

With these and many other objects in view which will more readily appear to those familiar with the art, as the structural features of the invention are better understood, the same consists in the novel construction, combination and arrangement of parts as hereinafter more fully described, illustrated, and claimed.

Though susceptible of structural modification and adaptation to various forms of bars and base plates, the preferred and practical embodiment of the invention is illustrated in the accompanying drawings in connection with the well known "Wolhaup- 70 ter" type of rail joint, in which—

Figure 1 is an end view of the Wolhaup- 75 ter type of rail joint embodying the improvements contemplated by the present invention to provide a crowned-base joint; the rails shown in section. Fig. 2 is a vertical transverse sectional view of the same joint at the center thereof, the rail ends shown in elevation. Fig. 3 is a central longitudinal sectional view of the joint, the 80 base plate shown in section, and the rails in elevation. Fig. 4 is a view similar to Fig. 3, illustrating a modification wherein the crowned-base may be provided by a rolling operation instead of pressing up the 85 crowned or raised rail seat, as shown in Fig. 3.

Like reference characters designate corresponding parts in the several figures of 90 the drawings.

According to the embodiment of the invention illustrated in the drawings, the crowned-base rail joint includes in its organization the rail ends R, the opposite side joint bars 1, 1, and a separate rail-supporting base plate 2 clamped in effective position beneath the rails in a manner characteristic of the Wolhaup- 95 ter type of rail joint referred to.

Each of the side joint bars 1 is of angle 100 bar formation and is provided with a main upright splice member 3 disposed within the fishing spaces of the rails and having at its upper edge an enlargement forming a bearing head 4, and formed with the lower edge 105 of the splice member 3 is the usual inclined foot flange 5 overlying and engaging the rail base flange. In addition to the splice mem-

ber and the foot flange thereof, each side joint bar has formed integrally with the outer edge of the foot flange thereof, a depending portion 6 arranged beyond the edges of the rail flanges and provided with an integral inwardly projecting horizontal base-flange or member 7, the base-flanges or members 7 of the opposite side bars lying parallel with the rail bottoms and adapted 10 to provide supporting and clamping shoulders, upon which rest opposite side edge portions of the separate rail-supporting base plate 2. In the Wolhaupler type of rail joint this separate base plate 2 is provided 15 at one side edge thereof with an upstanding abutment flange or shoulder 8, which is engaged by the edges of the rail base-flanges at one side of the joint, and said separate base plate is also usually of a corrugated design, 20 as shown in Figs. 1, 2 and 3 of the drawings, although it will be understood that this is not a necessary feature of the invention as the latter may be carried out with base plates either of a plain or corrugated type. 25 A distinctive feature of the present invention resides in utilizing a separate base plate having a crowned rail seat and support upon which the rail ends rest. According to the embodiment of the invention suggested in 30 Figs. 1, 2 and 3 of the drawings, the crowned or raised rail seat, designated by the reference number 9, may be formed in a suitable press or die, whose operations effect an upsetting or pressing up of the base plate preferably at the center, so as to provide a well defined seat to give the rail ends a base support at the center of the joint, while the remaining portions of the base plate are out of contact with the bottoms of the rails. 35 While there is shown in Fig. 3 of the drawings only a single raised or crowned rail seat provided on the base plate at the center of the joint, and under the ends of the rails, it will be understood that the provision of a pressed-up rail seat or seats may 40 be repeated at several points throughout the length of the joint, without departing from the invention, so long as the feature is preserved of having a crowning support for 45 the ends of the rails at the center of the joint, while the rails within the end portions of the joint are normally out of contact with the supporting seat or base, in order that the full effect of a crowned-base support for 50 the rail ends may be obtained. 55 By way of illustrating the modification that may be resorted to in carrying out the invention, there is shown in Fig. 4 of the drawings, a modified form of crowned rail seat and support. That is to say, according to the illustration of Fig. 4, it will be observed that a crowned rail seat and support 9^a may be provided for the rail ends at the center of the joint by a rolling operation 60 wherein the base plate is rolled on a curved

line. In this proposed embodiment of the invention, that is the one shown in Fig. 4 of the drawings, the end portions 9^b of the base plate are preferably flat and occupy a horizontal plane and are adapted to bear on the base flanges 7 for the full width of the ties. By reason of this construction the base plate is supported from the joint bars, over the ties, while the highest point of the base plate will be disposed under the rails at the center of the joint with the result of giving the same crowned-base support as the pressed-up seat 9 shown in Fig. 3 of the drawings. 70

Without regard to the design of the separate base plate employed, or the manner in which the crowned rail seat and support is provided, another important feature of the invention resides in having the bearing heads 4 at the upper edges of each of the splice members 3 disposed below and out of contact with the under sides of the rail heads. This is done in order that the heads 4 of the splice members will not be called upon to take any of the load from the rail head and to allow for any slight deflection of the base plate under the load but more especially to allow for the free vertical movement of the rail at the ends of the joint under the wave motion of the rolling loads. These heads have a pressing engagement with and against the rail webs in order that they will act as a fulcrum to the bolts in tightening up the lower portions of the joint and also has a pressing engagement with and against the rail webs in order to maintain the alignment of the rails. 95

From the foregoing, it is thought that the invention will be thoroughly understood without further description, but it is also to be understood that various changes in the form, proportion, and minor details of construction may be resorted to without departing from the spirit, or sacrificing any of the advantages of the invention. 105

I claim:

1. A rail joint including joint bars having base flanges, and a separate base plate clamped between said base flanges and the rail bottoms and having a crowned rail seating portion. 115
2. A rail joint including joint bars having inwardly projecting horizontal base flanges, and a separate base plate engaged with the edges of the base flanges at one side of the joint and clamped between the bottoms of the rails and the base flanges of the joint bars, said separate base plate having a crowned rail seating portion. 120
3. A rail joint including side joint bars, and a separate corrugated rail supporting base plate engaged by said bars and having a crowned rail seating portion. 125
4. A rail joint including joint bars arranged below and out of contact with the un- 130

der sides of the rail heads and having an engagement with the rail webs, and a separate base plate provided with a crowned rail seating portion.

5 5. A rail joint including joint bars arranged below and out of contact with the under sides of the rail heads and having an engagement with the rail webs, and a separate base plate engaged by said joint bars

10 and having a crowned rail seating portion.

6. A rail joint including joint bars having upright members within the fishing spaces and provided at their upper edges with bearing heads contacting with the rail

15 webs and disposed below and out of contact with the under sides of the rail heads, and a separate base plate held by said joint bars

beneath the rail bottoms and provided with a crowned rail seating portion.

7. A rail joint including side joint bars 20 arranged out of contact with the under sides of the rail heads and bearing against the rail webs, and a separate base plate held between the rail bottoms and the joint bars and provided with a raised rail seat adapt- 25 ed to be engaged by the rail ends at the center of the joint.

In testimony whereof I hereunto affix my signature in the presence of two witnesses.

BENJAMIN WOLHAUPTER.
